UNITED STATES PATENT OFFICE.

FRED LESLIE BROWN, OF EDMONDS, WASHINGTON.

CIGAR-MAKER'S BUNCH-ROLLER.

SPECIFICATION forming part of Letters Patent No. 651,778, dated June 12, 1900.

Application filed July 31, 1899. Serial No. 725,652. (No model.)

To all whom it may concern:

Be it known that I, FRED LESLIE BROWN, residing at Edmonds, in the county of Snohomish and State of Washington, have invented a new and Improved Cigar-Maker's Bunch-Roller, of which the following is a specification.

This invention relates to improvements in cigar-making means, and more particularly to that class of appliances adapted for use on a cigar-maker's bench or table.

In its general nature this invention comprehends a simple and economically-constructed appliance adapted to be fitted to the ordinary cigar-maker's bench or table and which has for its purpose to make or assist in the making of the bunch or filler composing the body of the cigar.

Furthermore, this invention seeks to provide an attachment of this character which can be easily manipulated by unskilled labor to quickly and properly bind the bunch and by the use of which the filler can be worked drier than can be effected by hand operation, whereby a freer smoking of the cigar is produced and which is also especially adapted for rolling scrap or short-filler as well as long-filler staple.

Another object of my invention is to provide an appliance of the character stated that will make hand or mold work into a tight or loose bunch, and which is capable of rolling the bunch to any shape desired.

With other objects in view my invention consists in the peculiar combination and novel arrangement of parts, such as will be first described in detail and then pointed out in the appended claims, reference being had to the accompanying drawings, in which—

Figure 1 is a perspective view illustrating my invention as set up for use. Fig. 2 is a detail transverse section of the bunch-forming rolls, the parts being at their normal position ready to receive the loose filler-bunch. Fig. 3 illustrates the bunch-forming rolls partly turned, the bunch partly formed, and the binder partly wound upon the bunch. Fig. 4 illustrates the bunch completely rolled. Fig. 5 illustrates the forming-rolls as returned to their "throw-off" position. Fig. 6 is a detail perspective view of the cutting-board with the bunching devices attached. Fig. 7 is a

detail view of the cutting-board with the main bunching-roll detached. Figs. 8 and 9 are respectively views of the inner and outer sets of one of the supporting-brackets. Figs. 10 and 11 are similar views of another supporting-bracket. Fig. 12 is a detail view of the main bunch-forming roll; and Fig. 13 is a detail view, hereinafter specifically referred to.

In its practical construction my improved appliance is secured on the back end of a cigar-maker's board substantially in the manner illustrated in Fig. 1, and it, together with the board, secured in place after the table 1 has been suitably cut out to allow for a proper fitting of the said board and the appliance thereon.

The appliance *per se* comprises a pair of forming-rolls, a receiver, a forming or rolling apron, and means for adjusting the slack of the apron, whereby to govern the size of the bunch to be rolled, and supporting-brackets for the said several parts.

By referring now more particularly to Figs. 2, 3, 4, and 5 it will be seen the pair of rolls are journaled in a horizontal plane with their peripheral edges in close relation; but one of the rolls, (the outer,) which I shall term the "receiver-roll," as it has pockets to receive the tobacco for forming the bunch from the hands of the operator, is of a much larger diameter than the other roll, which I term the "presser-roll." The presser-roll 2 is detachably journaled in the supporting-brackets 3, 4, that project rearwardly from the back of the cutting-board 5, the outer surface of the said presser-roll being preferably of a yielding character, such as rubber or felt, as indicated by 2^a; but this feature is not absolutely necessary, as the said outer surface may be of a solid nature. The receiver-roll 6 is loosely mounted upon a shaft 6^a, having square end journals 6^b, adapted to be detachably fitted into non-circular pockets 7, formed upon the ends of the brackets 3, 4, as clearly shown in Fig. 6, and one end (or both) of the roll is secured to a spring 8, which has its other end secured to the shaft, (see Fig. 12,) the said spring connection being so made that the roll 6 will be normally rotated outward, (see arrow, Fig. 13,) so as to bring the receiving-pocket Y uppermost and in a convenient position to receive the filler or binder from the

hands of the operator, and to insure such adjustment of the roll 6 when it is swung back by the spring said roll has a lateral stop-lug 6^a, that engages a stop-lug 6^a upon the adjacent bracket, said lug 6^a also serving to limit the forward rotation of the roll 6 by reason of its engagement with the upper face of the lug 6^a. 9 indicates an endless flexible apron that is made secure to the roll 6, 10 passed over the presser-roll 5 and over an adjustable guide-roll 10.

In practice the apron 9 is made sufficiently slack to permit its being pressed into the grooves or pockets X Y in the periphery of 15 the roll 6.

The pockets X Y extend nearly the full length of the roll and are parallelly arranged and have their ends bulged outward, as X' Y', whereby to make the pockets the deepest at 20 the center where the cigar-bunch is intended to be rolled, the thickest. It should, however, be stated that the exact contour of the said pockets, as also the external contour of the presser-roll, may vary to suit the shape 25 of the cigar or bunch it is desired to make.

The pockets X Y have their inner edges terminating in an extenuated concavo-convex curve, as shown, whereby to provide for a gradual rolling and pressing of the 30 bunch, as will be presently more fully explained.

The main roll has its ends formed with transverse grooveways 11 11 to receive the guide ends of the pull-cord or cable-sections 35 12 12, that are made fast to the rolls, passed down and connected with the treadle, as clearly shown in Fig. 1.

The adjustable roll 10 has its ends passed through diagonally - arranged slots in the 40 brackets 3 4, and said ends are journaled in eyes 16^a, formed on the ends of the threaded adjustable screw-shafts 16, that pass through a pair of apertured ears 17, formed as a part of the said brackets 3 4. Each screw-shaft 45 16 carries a screw-nut 18, that operates between the ears 17, the proper manipulation of which will take up or make slack the apron, it being obvious that to set the apron the operator has only to turn the nuts 18 in the direction desired, which operation can be readily effected without disarranging any of the parts of the appliance or the cutting-board.

The manner in which my improvement is operated is best explained as follows, assuming the parts to be in the normal position, as indicated in Fig. 2: The filler is placed upon the apron portion over the pocket Y (which the spring 8 brings into position) and pressed, together with the apron, into said pocket Y. 55 One end of the binder is then tucked into said pocket back of the filler, the roll 6 being then slightly turned by treadle manipulation to bring the filler or bunch into engagement with the presser-roll 2, which then crowds the 60 filler or bunch between the space between the two rolls until the bunch begins to bind or work harder, thereby grasping or holding the 65

end of the binder, it being understood that the presser-roll, by reason of frictional contact, will rotate toward the roll 6, and as the 70 apron is then drawn in an inward direction it follows that as the two rolls crowd the bunch between them the movement of the apron will tend to rotate the said bunch at the same time. After the filler is placed into 75 position and has received a partial rotation or compression the binder (which is then held secure at one end by reason of partial compression of filler and end of binder in pocket) is then spread out, and steady pressure is then applied to the treadle until the roll 6 revolves around and is stopped by its stop-lug engaging the stop-lug or bank upon the brackets, at which time the next pocket X will be in 80 position to receive the rolled bunch, which by expansive force seats itself in the said pocket X, and pressure being then released from the treadle the spring upon the roll 6 will revolve the said roll in a reverse direction and carry with it the rolled and bound filler-bunch and 85 discharge the same from between roll 6 and roll 2, as indicated in Fig. 5.

The brackets are made of light metal; the rollers of metal, wood, rubber, or papier-mâché, and the apron of cloth, leather, or rubber cloth. 90

From the foregoing, taken in connection with the accompanying drawings, it is thought the advantages and complete operation of my invention will be readily understood. 100

It will be observed that the construction is of a very simple and economical character and takes up but a minimum amount of space upon the table and in such a manner as not in the slightest impair the full use thereof, 105 it being so arranged that the operator can quickly wrap or bind the bunches as he makes them. The construction is of such character and the operation so simple that a boy can be readily instructed to operate the 110 machine. Furthermore, by arranging the apron in the manner stated the appliance can be quickly adjusted to form and bind bunches of various sizes.

Having thus described my invention, what 115 I claim, and desire to secure by Letters Patent, is—

1. A tobacco-bunching machine, comprising means for rolling the bunch, including a pair of coacting rolls, and an endless apron made fast to one roll and passed over both rolls; a tension-guide for the apron, one of said rolls having a plurality of receiving-cavities in its periphery; manually-operated means for turning the rolls in one direction to roll the bunch and automatically-operating means for bringing the cavity-roll in a reverse direction to discharge the rolled bunch. 120

2. A cigar-bunching machine, comprising a pair of rolls rotatable toward each other, one of said rolls having two pockets, the first being adapted to receive the filler; an endless apron coacting with the said rolls; a tension-guide for the said apron; manually-op- 125 130

erated means for moving the rolls and apron in one direction, whereby to compress the filler between the rolls, and automatically-operating means for moving the rolls and the 5 apron in a reverse direction to discharge the formed filler when the second pocket of the pocket-roll is brought into a position contiguous with the formed filler.

3. An appliance for the purposes described, 10 comprising a pair of coacting opposing rolls, one of the said rolls having a pair of peripheral receiving pockets or depressions; an endless apron fixedly secured to the pocketed roll, passed over said roll, and the other 15 roll; a guide for the apron, said rolls being held to rotate toward each other, whereby to carry the filler between them and simultaneously move the apron in one direction to roll the filler and binder as the filler is being 20 compressed, and means for automatically moving the pocketed roll in a reverse direction as specified.

4. An appliance for the purposes described, 25 comprising an outer reversely-rotatable roll, having a plurality of peripheral pockets; the presser-roll; supporting-brackets for the said rolls; an endless apron secured to the pocketed roll, and passed over the presser-roll; a guide-roll for the apron, and means for adjusting the guide-roll, for the purposes specified.

5. The combination with the cutting-table; 30 of the brackets extended rearwardly therefrom; the reversely-rotatable receiving-roll having pockets to receive the filler-bunch; the 35 coacting presser-roll detachably journaled

in the said brackets; the endless apron secured to the reversely-rotatable receiver-roll; said apron passing thereover and over the presser-roll; a guide-roll around which the 40 apron passes mounted in the supporting-brackets; a spring mechanism for turning the receiver-roll in one direction; a treadle mechanism connected with the said receiver-roll for rotating it in a reversed direction 45 against the tension of the spring; and a stop mechanism for limiting the movement of the said roll in the opposite direction, all being arranged substantially as shown and for the purposes described. 50

6. A tobacco-bunching machine, comprising a supporting-frame; a large roller and a smaller roller having coacting surfaces, each roller having a pair of peripheral cavities or pockets held in parallel planes; an apron 55 passed over the two rollers, said apron having slack; an adjustable guide-roller for the apron, said apron being made fast to the large roller, the first cavity of the large roller being arranged to receive the loose 60 bunch or filler, the second cavity forming a pocket into which the rolled and wrapped bunch is adapted to seat; and spring-actuated devices for reversing the movement of the rolls, when the second cavity moves in a line 65 with the rolled bunch, substantially as shown and for the purposes described.
